(57) **CLAIM**

The ornamental design for a globe for a suspended luminaire, as shown and described.

DESCRIPTION

FIG. 1 is a perspective view of a luminaire showing the new design;

FIG. 2 is a first side elevational view thereof;

FIG. 3 is a second side elevational view thereof seen rotated 90° from the first elevational view of FIG. 2;

FIG. 4 is a bottom view thereof; and,

FIG. 5 is a top plan view thereof.

The broken line environmental showing is for illustrative purposes only and forms no part of the claimed design.
